UNITED STATES PATENT OFFICE.

ARTHUR T. MCWANE, OF BIRMINGHAM, ALABAMA.

WINDOW GUARD.

Application filed June 8, 1923. Serial No. 644,260.

This invention relates to window guards and has for its object the provision of vertically sliding sashes of a window with sliding metal grills or guards which will make 5 the window burglar proof.

My invention is more particularly concerned with the detachable mounting of the guard on the lower sash and contemplates the provision of manually controllable means 10 to connect or disconnect the guard from the sash.

My invention further contemplates the provision of means to support the guard in its raised positions so as to prevent its weight 15 overbalancing the sash weights, it being obviously desirable that if the window is to be operated both with and without the guard, its sash weights should be adapted to balance only the window sash.

20 My invention further contemplates the application of a guard in any desired manner to the upper sash and the provision of weights for the upper sash adapted to counterbalance both the sash and its guard.

25 The special advantage of my invention lies in the fact that the guard can be detached from the lower sash, which is normally the one operated during the day, and concealed so that there is no suggestion of the 30 provision of the guard and thus the appearance of the window is not detracted from.

A further important feature of my invention is the provision of a novel latch means 35 for connecting the guard to the sash so that it cannot be unlatched, when the window is raised, without taking out the sash.

My invention also contemplates the novel 40 details of construction and arrangements of parts, which in their preferred embodiment only are illustrated in the accompanying drawings, in which:—

Fig. 1 is a front elevation of a window partly broken away and showing the upper and lower guards in dotted lines in position 45 assumed when the windows are closed.

Fig. 2 is a similar view of the opposite side of the window illustrating a modified type of latch shown in Fig. 7.

Fig. 3 is a vertical central cross-sectional view through the window illustrated in 50 Fig. 1.

Fig. 4 is an enlarged detail view of the corner of the lower sash and adjacent frame broken away to show the co-related recesses 55 in the latch and frame and illustrating the latch mechanism in side elevation.

Fig. 5 is a view showing part of the lower sash and guard in elevation with the window frame and sash broken away, as shown in Fig. 4, and indicating the latch for supporting the weight of the guard when raised. 60

Fig. 6 is a cross-sectional view, taken on the line 6—6 of Fig. 5, and shows in plan that part of the bottom sill of the window frame underlying the lower sash. 65

Fig. 7 is a cross-sectional view taken on the line 7—7 of Fig. 2 and showing a modified type of latch operating means.

Similar reference numerals refer to similar parts throughout the drawings. 70

Referring to the embodiment of my invention illustrated in Figs. 1, 3, 4 and 5, I show the lower sash 10 and the upper sash 11 mounted to slide vertically in the usual guides in a window frame 12. I prefer to 75 mount a suitable guard on the top rail 13 of the upper sash in such manner as not to be removable while the sash is in the frame, said guard comprising a base 14 having downturned ears secured to the ends of the 80 rail 13. Upright bars 15 on said base work through suitable openings in the top frame member 16 and enter the open space in the wall above the window. This top guard may be dispensed with, if desired, and it is 85 to be understood that its use in conjunction with the guard of the lower sash is optional. Where such a guard is used the upper sash will have sash weights 37 which will counterbalance the upper sash and its guard. The 90 lower sash on the contrary will have only the sash weights 38 adapted to balance the weight of the lower sash alone.

In the bottom rail 17 of the lower sash at each end I provide a countersunk recess 95 or seat 18 to the inner wall of which is attached by screws, or in any other manner, a latch keeper or detent 19. The lower window guard is a metal grill or frame of any suitable design, that shown comprising a top member 20 having cast integral therewith or otherwise connected thereto depending bars or rods 21 which form the guard proper. The top member 20 is preferably received in a transverse recess 20^a 100 in the rail 17 and has at each end a countersunk recess in which a latch 22 is pivotally mounted by a rivet or pivot pin 23, the latch being adapted to enter the recess 18 so as to engage the keeper 19. The latch end and 105 the keeper are suitably bevelled to permit the keeper to move down into interlocking 110

engagement with the latch when the sash is fully lowered. In the side member 24 of the window frame is a recess 25 covered over by a countersunk plate 26 having an outwardly swinging hinged door 27 therein which is pressed towards the window sash by a coil spring 28 mounted on the hinge pin of the door. This door 27 stands opposite the latch 22 when the window is lowered and serves as a spring recess to force and hold the latch in interlocked relation with its keeper and yet which will yield to permit the latch to be released. A latch releasing pin 29 is mounted to slide in the rail 17 opposite each latch and it is adapted when moved away from the center of the window, against the action of a coil spring 30, to engage and force the latch outwardly against the action of spring 28 sufficiently to unlatch it from the keeper 19 and thus permit the lower sash 10 to be raised without carrying with it the window guard. It is obvious that when the guard is latched to the window and its latches 20 have been raised above their respective doors 27, it will be impossible to force the latches outwardly sufficiently to disengage them from the detent 19, as the frame holds the latches in engagement with their keepers, as is clearly apparent in the view shown in Fig. 5. The guard is thus held positively interlocked with the sash when it has been raised to open the window to any extent and it is not possible for a burglar by inserting his hand through the guard to detach it from the window.

Inasmuch as the latching of the guard to the lower sash will unbalance its sash weights it is necessary to provide stop means to hold the window and guard in operating positions and to this end I provide in one or more of the guard bars 21 a series of notches or teeth 31 which are adapted to be engaged by a stop plate 32 pivotally connected to an attachment plate 33 secured to the bottom rail 34 of the window frame. If desired the top member 20 can be countersunk at 35 to receive in the pocket thus formed the members 32, 33 when the stop is folded down out of operating position.

In operation, when it is desired to conceal the lower sash guard, the lower sash 10 is closed, the latch pins 29 are pressed outwardly to disengage the latches 22 from the detents 19. While held in this position the window is lifted by grasping the hand-holds 35, which are disposed conveniently to the latch pins, leaving the guard concealed below the inside plate 36 of the frame. When it is desired to use the guard the lower sash is closed, the latch members 22 and 19 automatically interlock and then by grasping the hand grips 35 on the sash, the sash and guard can be raised together, and when adjusted to the desired height

the stop plate 32 is swung up into engagement with the teeth 31 and the combined window and guard are held in this position. The window can be raised further without disturbing the stop 32, but when it is desired to lower the window the stop 32 must be disengaged from the teeth 31 and folded down against the plate 32. 70

In Figs. 2 and 7 I show a modification of my invention, wherein the recess 18^a for the latch is cut in the inner side face of the bottom rail 17 in position to be overhung by the adjacent inside guide strip 37. The recess 38 to permit the latch 22, here pivoted to the ends of the member 20 to swing inwardly, to move clear of the detent 19 is formed in the outside face of this strip 37. A bell crank lever 39 is pivoted in the recess 18^a and has a pin 40 adapted to engage the latch and force it outwardly when the lever is depressed, a coil spring 41 being provided to restore the lever to initial position. The operation of this device is the same as that described, the latch 22 being held, by its engagement with the guide rail 37, in interlocked relation with the detent 19 when raised with the sash to operating position. 85

Having thus described my invention, what I claim as new and desire to secure by Letters Patent, is:— 95

1. A sash guard having means operable to interlock it with a sash, and readily accessible means to provide for unlocking the guard from the sash which is operable only when the sash is in its closed position. 100

2. In combination, a sash guard, a sash, elements which co-act to interlock the guard and sash for joint operation, means to unlock said elements when the sash is lowered and means to hold the said elements against unlocking when the sash is raised. 105

3. In combination with a window frame and a vertically sliding sash having a detent means, of a guard having manually controllable latch means to detachably connect it to said sash detent means, said latch being disposed to be held against unlatching by the window frame when the sash is raised, and a recess in the frame to permit the latch means when the sash is lowered being disengaged from the detent means. 110

4. A window guard in accordance with claim 3, in which the frame is provided with a countersunk cover plate for the recess therein, said plate having an outwardly opening spring-pressed door therein disposed to come opposite to said latch means when the sash is lowered and adapted to yield to permit the latch means to enter the recess when moved away from said detent means. 120

5. In combination with a vertically sliding sash and a window frame therefor, of a guard slidable through said frame and 130

having at its upper end latch elements, said sash having at its bottom end countersunk co-acting latch elements, exposed manually controllable means to disengage said latch elements and means at the bottom only of the frame to provide for the necessary relative movement between said latch elements to engage or disengage them.

6. A window guard means in accordance with claim 5, in which the said sash is provided with latch releasing means closely associated with sash lifting grips.

7. In combination with a window frame, of a vertically slidable sash having counter-balancing weights suitably connected thereto, a guard detachably connected thereto, and stop means to support the weight of

the guard when in any operating position to prevent the added weight of the guard overbalancing the counterweights.

8. In combination, a window frame, a pair of vertically slidable sashes mounted therein, a guard fixedly attached to the top of the upper sash, weights to counterbalance the upper sash and guard, a lower guard, means to detachably connect it to the lower sash, weights to counterbalance only the lower sash, and pawl and ratchet means to support the weight of the lower guard when raised with the lower sash to different operating positions.

In testimony whereof I affix my signature.

ARTHUR T. McWANE.
